[57] CLAIM

The ornamental design for a rocket launcher anti-aircraft sight adaptor or the like, as shown and described.

DESCRIPTION

FIG. 1 is a front elevational view of a rocket launcher anti-aircraft sight adapter or the like showing my new design;

FIG. 2 is a rear elevational view thereof;

FIG. 3 is a top plan view thereof;

FIG. 4 is a bottom plan view thereof;
FIG. 5 is a side elevational view thereof, the opposite side elevational view being a mirror image of that shown; and

FIG. 6 is a front perspective view thereof.

FIG. 1

FIG. 2

FIG. 3

FIG. 4

FIG. 5

FIG. 6
